ASSIGNEES TO WILDMAN MFG. CO., A CORPORATION OF PENNSYLVANIA.

STOP-MOTION FOR KNITTING-MACHINES.

1,081,180.

Specification of Letters Patent. Patented Dec. 9, 1913.

Application filed March 7, 1913. Serial No. 752,799.

To all whom it may concern:

Be it known that we, FRANK B. WILDMAN and GEORGE L. BALLARD, a citizen of the United States and a subject of the King of Great Britain, respectively, and residents of Norristown, Pennsylvania, have invented certain new and useful Improvements in Stop-Motions for Knitting-Machines, of which the following is a specification.

The invention relates to stop motions for knitting machines of that type in which the thread passes over a sweep finger arranged above the knitting head, and thence it passes toward the extended axial line of the knitting head over a guide hook, and thence past a releasing finger, which is held up by contact with the thread. The said releasing finger, when freed from contact with the thread either by the breaking thereof or by the dropping of the thread from the guide hook, will fall and cause the operation of mechanism within the head of the stop motion, which, in turn, controls the let-off mechanism.

The present invention consists in the features of construction and arrangement and combination of parts hereinafter described and particularly defined by the appended claims.

In the accompanying drawings Figure 1 is a side view of a stop motion head with one set of controlling devices combined therewith; Fig. 2 is a plan view of the parts shown in Fig. 1; Fig. 3 is a view looking from the left of Fig. 1 substantially in the direction of the arrow x.

In these drawings, 1 is the stop motion head, which is shown in general outline, and which may contain any suitable mechanism to effect the let-off action when the releasing finger 2 drops, said releasing finger, when the thread is being fed normally, being maintained in its upright position by engaging the said thread, the finger having lateral extensions 2', 2'', and said finger being combined with a guide frame 3.

The thread is guided to the releasing finger as in prior practice by a hook 4 on a rock shaft 5 journaled in the stop motion head and in a bearing 6 at the outer end of the radially extending arm 7, the said arm being composed of a suitable rod. At its outer end the shaft 5 has a downwardly inclined extension 8 engaged by the arm 9 of a sweep finger 10. This sweep finger is formed in one piece with its arm 9, and in one piece also with its journal portion or extension 11, which extends down from the main body of the sweep finger, and is bent at right angles at its lower end, finding a bearing at this point on the pin or bracket 12 fixed in any suitable manner to the bracket or head 13 at the outer end of the rod 7. The sweep finger has a curved or segmental end 14 to receive and guide the thread. The rock shaft 5 is under tension of a spring arranged in any suitable manner, for instance, within the head 1, and not shown, the said spring tending to keep the rock shaft in the position indicated in the drawings, and tending also to keep the sweep finger in the position shown. The journal pin or bracket 12 of the sweep finger is arranged at an inclination to a vertical line, and thus the sweep finger, in turning, swings along an inclined plane.

The sweep finger is combined with guard means, and in the present case this guard means consists of a plate of sheet metal or other suitable material 15 secured to the under side of the bracket 13, as, for instance, by the screw 16, the said guard plate extending laterally from the bracket 13 in the same direction that the sweep finger extends, and the general position of the guard plate being inclined downwardly toward the axis of the stop motion head, it also inclining downwardly, as shown in Figs. 1 and 3, in a lateral direction from the bracket 13. The guard plate thus extends in a plane substantially parallel to the inclined plane in which the sweep finger moves. It is provided with two arms, one 17 and the other 18, the latter having its terminal portion 19 extending back toward the bracket 13, and at an angle to the main portion 18 of the outer arm or finger. The guard also includes a lower bearing for the thread; and while this second portion of the guard may be varied in construction in the particular organization disclosed, I employ for lightness and simplicity, and also economy, a guard member composed of wire. This wire has one arm or portion 20 extending from the under side of the outer end of the head or bracket 13 downwardly, its general trend being toward the stop motion head, and also laterally in relation to the bracket or head 13. At the lower end of the arm 20 the wire is continued horizon-

110

tally, as at 21, in a direction substantially at right angles to the vertical plane in which the arm 7 and head or bracket 13 lie, this horizontal portion being continued by an upwardly inclined portion 22, the end of which is secured by a screw at 23 to the under side of the bracket 13. The arm 17 of the guard plate 10 has its end partly embracing the wire guard member 20, and the end of the portion 19 of the guard plate extends to a point slightly above the guard wire 20, and at some distance away from the junction of the wire members 20, 21. The opening 24 between the arms 17 and 18 of the guard member 10 widens out from its upper end, where the sweep finger is normally located, downwardly, as best shown in Fig. 2, so that as the sweep finger swings, its end which normally overlies the arm 18 will gradually move to a point over the opening 24, so that the thread may leave the sweep finger and fall, it passing, in this action through the crevice at 24' between the end of the finger 19 and the guard wire 20.

In the operation of the device the thread from the supply bobbin passes upwardly, as indicated at y, Fig. 1, through the upper end of the opening 24, thence over the curved end of the sweep finger to the guide hook 4, as shown in Fig. 1, passing over this and then down past the extensions 2', 2'', of the releasing finger and past the guard 3. Under normal conditions the thread will pass along the course just indicated, the tension on the rock shaft 5 being sufficient to hold the hook 4, together with the sweep finger, in the positions indicated, to properly guide the thread. If, from any cause, the free passage of the thread is interfered with and consequently the tension thereon is increased, the sweep finger will turn provided the tension is sufficient to move it, and in turning, its arm 9, acting against the extension 8, will turn the rock shaft 5, remove the guide hook 4 from the thread, which is thus allowed to drop, freeing itself from the fingers 2', 2'', of the releasing finger 2, which thereupon will drop and operate the mechanism within the stop motion head 1. In swinging under the tension just mentioned, the end of the sweep finger will be carried from over the arm 18 of the guard plate 10, and to a point above or adjacent the lower part of the opening 24, and the thread will drop from this finger if the tension is maintained. In dropping from the sweep finger, it will move down along the guard wire 20, and pass through the crevice between said wire and the end of the finger 19, and thus drop entirely from the controlling devices of the stop motion head so that sufficient yarn will be provided to supply the machine while it is coming to rest after the let-off has been operated.

It will be noticed that the sweep finger swings in an inclined plane downwardly so as to facilitate the dropping off of the thread, and the guard being arranged in an inclined plane substantially parallel to the inclined plane in which the sweep finger moves, will serve to guard the action of the sweep finger and thread until the sweep finger has reached the point predetermined upon at which the thread is to drop off.

One function of the guard is to afford a bearing point for the thread after it drops off from the guide hook 4, so that the pull of the thread from this bearing point will be substantially in the same plane in which the sweep finger operates. In other words, it will be noticed that the bearing for the thread afforded by the portion of the guard at 21 will cause the thread to pull in the direct line of movement of the sweep finger, this pull taking place, of course, after the thread has dropped from the hook and is resting on the wire 21. By reason of this lower guide or support for the thread the pull is in such a direction that the sweep, together with its journals or bearings, will be relieved from twisting or torsional strain. Should an inexperienced operator, through inadvertence, misthread the device by carrying the thread below the guard 21 after it leaves the sweep instead of above the wire guard, as indicated in the drawings, this will not interfere with the proper operation of the mechanism, for in this case also the initial pull on the thread before it drops from the hook 4 will be in the direction in which the sweep is adapted to move.

It will be observed that with my improved guard consisting of the upper and lower members, whether they be formed of the plate and wire described or otherwise formed, there are no ends left exposed over which a loop or snarl of thread may be thrown and caught, which would result in breaking of the thread. In practice the yarn frequently proceeds by a jerky motion, and loop formations are sometimes present in the yarn due to this jerky action, and these loops will engage projecting parts adjacent the sweep finger if such projecting parts are present in the construction by an action similar to that of lassoing, and where guards have been provided heretofore with terminal exposed ends, these loops would encircle the same and would then be drawn tight thereon, resulting in a broken yarn end. It will be noticed that in my present construction a snarl or loop can not catch on the guard, because its forward finger 19 is brought around to be shielded or guarded by the wire guard member 20, and the whole guard acts to prevent snarls or loops from catching on the sweep finger. It will be noticed that the edge of the arm 18 of the

guard is inclined, and converges toward the wire arm 21, and should a loop encircle these parts it would naturally free itself therefrom when slightly drawn upon. The 5 wire guard tapers toward the yarn side of the device, namely: the side on which the yarn is introduced, and should a snarl lodge on this tapered end it will run off at the point when the yarn is pulled.

10 It will be observed that with the sweep finger swinging in an inclined plane and with the bearing 21 provided to cause the pull on the sweep finger in a plane substantially coincident with the plane of movement of said sweep finger after the thread leaves the hook 4, the device is rendered more sensitive and the sweep finger is relieved from the strain which would be brought thereon were the pull of the thread 15 in a direction substantially vertical. It would take considerably more power to swing the finger and allow the thread to drop off were the bearing at 21 not provided. With the arrangement disclosed, the 20 thread drops off from the sweep under a light pull.

Referring to the function of the bearing 21, should the operator inadvertently thread the yarn below this bearing instead of above it, it will be understood that if this portion were not provided and the thread was passed after leaving the sweep below the portion 20 and thence to the hook 4, the thread would be locked between the sweep 25 and the member 20, when the sweep moves to its low limit, and would not drop off, but with the lower wire 21 converging, as it does, toward the wire 20, the thread, if passed below these parts and pulled upon, 30 would be caused to move toward their point of convergence, and thus it will drop from the sweep.

It will be observed that the sweep swings within the limits of the guard, that is to 45 say, it is guarded throughout its movement. Further, it will be clear that whether the guard be formed of the sheet metal member and the wire portion, or be otherwise formed, the end of the sweep is guarded in 50 all positions, the guard presenting an edge directed laterally and unbroken from end to end except at an intermediate point where the crevice occurs for the inlet and outlet of the thread, this in the particular construction selected to illustrate the features 55 of the invention being between the end of the finger 19 and the bearing member 20, this crevice being of a width to permit threading of the yarn through it or to permit 60 the dropping through of the thread when the sweep finger swings down to its low limit. This construction, therefore, with the laterally directed edge of the guard substantially intact from its upper to its lower 65 end, presents no protuberance or ends upon

which the thread may catch. The end of the finger 14 is guarded by a portion of 20, and any thread engaging the portion 20 would, under the pull thereof, slip off of the point of juncture of the portions 20, 21.

We claim as our invention:

1. In combination in a stop motion for knitting machines, a guide for the thread, a sweep finger pivoted to swing in a plane inclined downwardly from its upper position toward the guide, a connection between the sweep finger and guide, a releasing finger, and a guard arranged in an inclined plane parallel to the plane of movement of the sweep, said sweep moving substantially within the limits of the guard from its thread holding to its thread releasing position, substantially as described. 70

2. In combination in a stop motion for knitting machines, a guide for the thread, a sweep finger pivoted to swing in a plane inclined downwardly from its upper position toward the guide, a connection between the sweep and guide, a releasing finger, and a guard extending in an inclined plane substantially parallel to the plane in which the sweep finger swings, said guard having a bearing for the thread at its lower end extending in a direction transverse to the plane of the path of the thread from the sweep finger to the guide, said bearing receiving the thread when it falls from the guide, substantially as described. 85

3. In combination in a stop motion for knitting machines, a guide for the thread, a sweep finger pivoted to swing in a plane inclined downwardly from its upper position toward the guide, a connection between the sweep and guide, a releasing finger, and a guard extending in an inclined plane substantially parallel to the plane in which the sweep finger swings, said guard having a bearing for the thread at its lower end extending in a direction transverse to the plane of the path of the thread from the sweep finger to the guide, said bearing receiving the thread when it falls from the guide, said bearing being below the low thread releasing limit of the swinging movement of the sweep finger, substantially as 90 described. 100

4. In combination in a stop motion for knitting machines, a guide, a sweep finger pivoted to swing in an inclined plane downwardly toward the guide, a connection between the sweep finger and guide, a guard extending substantially parallel with the plane of movement of the sweep finger, said guard having an opening therein to receive the thread over which opening the sweep 105 finger moves, substantially as described. 110

5. In combination in a stop motion for knitting machines, a sweep finger pivotally mounted, a guard extending substantially parallel with the plane of movement of the 115

sweep finger and having an unbroken edge except an opening for the passage of the thread to or from the sweep finger, substantially as described.

6. In combination in a stop motion for knitting machines, a support, a sweep finger pivotally mounted thereon and extending laterally therefrom, a guard extending laterally from the support and in a plane substantially parallel with the plane of movement of the sweep finger, said guard having its laterally directed edge substantially intact from end to end, excepting an inlet opening at an intermediate point leading 15 to the interior opening of the guard, substantially as described.

7. In combination in a stop motion for knitting machines, a support, a pivoted sweep finger, a guard therefor extending in a plane substantially parallel with the plane of movement of the finger, said guard having a finger with an opening for the thread on the inner side thereof, a portion of said guard lying adjacent the end of the finger 25 but leaving an opening between for the inlet or outlet of the thread, substantially as described.

8. In combination in a stop motion for knitting machines, a support, a pivoted sweep finger, a guard therefor extending in a plane substantially parallel with the plane of movement of the finger, said guard having a finger with an opening for the thread on the inner side thereof, a portion of said 30 guard lying adjacent the end of the finger but leaving an opening between for the inlet or outlet of the thread, said finger having its edge extending laterally outwardly and thence inwardly in respect to the support, substantially as described.

9. In combination in a stop motion for knitting machines, a pivotally mounted sweep movable in an inclined plane, a guard extending parallel to the plane of movement 45 of the sweep finger, said guard having a bearing portion at its lower end between the sweep finger and the axial center of the machine, the laterally directed edge of the guard converging with said bearing portion, substantially as described.

10. In combination in a stop motion for knitting machines, a stop motion head, a support, a sweep finger pivotally mounted on said support to swing in an inclined 55 plane toward the axial center of the head, a guard extending in a plane substantially parallel to the plane of movement of the sweep and laterally from the support, the edge of said guard extending from its upper end downwardly toward the axial center of the head, substantially as described.

11. In combination in a stop motion for knitting machines, a sweep finger pivotally mounted and a guard having a finger with 65 an opening on its inner side over which

the sweep finger moves, which opening receives the thread, substantially as described.

12. In combination in a stop motion for knitting machines, a sweep finger pivotally mounted, a guard having a finger with an opening on its inner side over which the sweep finger moves, which opening receives the thread, and a lower bearing for the thread at a point along the plane of the course of the thread beyond that at which the sweep finger releases the thread, substantially as described.

13. In combination in a stop motion for knitting machines, a stop motion head, a guide adjacent said head, a releasing finger, a sweep finger pivotally mounted to swing in an inclined plane toward the axis of the stop motion head when the tension on the yarn increases, a guard extending in a plane parallel with the plane of movement of the sweep finger and slotted to receive the thread, the said sweep finger moving over the said slot, which slot is open at its lower end, substantially as described.

14. In combination in a stop motion for knitting machines, a stop motion head, a guide adjacent said head, a releasing finger, a sweep finger pivotally mounted to swing in an inclined plane toward the axis of the stop motion head when the tension on the yarn increases, a guard extending in a plane parallel with the plane of movement of the sweep finger and slotted to receive the thread, the said sweep finger moving over the said slot, which slot is open at its lower end, and a bearing on said guard for the thread located at a point nearer the stop motion head than the mouth of the slot, substantially as described.

15. In combination in a stop motion for knitting machines, a sweep pivotally mounted to swing in an inclined plane toward the axial center of the knitting machine, a guard extending in a plane substantially parallel with the plane of movement of the sweep finger, the lower edge of said guard forming a bearing for the thread between the sweep when in normal position and the axial center of the machine, substantially as described.

16. In combination in a stop motion for knitting machines, a sweep pivotally mounted to swing in an inclined plane toward the axial center of the knitting machine, a guard extending in a plane substantially parallel with the plane of movement of the sweep finger, the lower edge of said guard forming a bearing for the thread between the sweep when in normal position and the axial center of the machine, said lower bearing consisting of a wire member, substantially as described.

17. In combination in a stop motion for knitting machines, a pivoted sweep finger and a guard consisting partly of a sheet

metal piece having a finger to receive the thread on its inner side and a wire member forming a bearing for the thread at a point between the sweep finger and the axial center of the knitting head, said wire member having a portion lying adjacent the end of the sheet metal finger to guard the same but to leave an opening for the passage of the thread, substantially as described.

18. In combination in a stop motion for knitting machines, a sweep finger pivotally mounted, a guard consisting of a sheet metal portion having a finger to receive the thread on its inner side, and a wire member at a point between the sheet metal portion and the axial center of the knitting machine, said wire member extending in a direction transverse to the plane of the course of the thread after leaving the sweep finger, said wire member having an angular extension extending past the end of the guard finger, said sweep finger moving in an inclined plane and the guard being arranged in a plane substantially parallel to the plane of movement of the sweep finger, substantially as described.

19. In combination a support, a sweep finger pivotally mounted to swing in an inclined plane, a sheet metal guard mem-

ber secured to the support and having a finger portion for receiving the thread on its inner side, and a wire member having a portion extending transversely of the plane of the course of the thread and forming a lower bearing to receive the thread at a point between the sweep and the axial center of the machine, said wire member having an upwardly and inwardly inclined portion extending adjacent to and past the end of the guard finger leaving a threading opening between, said wire member also being carried by the said support, substantially as described.

20. In combination a pivoted sweep, and a guard over which the sweep swings, said guard presenting an inner edge directed toward the pivot of sweep and receiving the thread at said inner edge, said sweep swinging to and from the discharge end of the guard, substantially as described.

In testimony whereof, we affix our signatures in presence of two witnesses.
